(57) **CLAIM**

The ornamental design for a boat anchor hook as shown and described.

DESCRIPTION

FIG. 1 is a perspective view of a boat anchor hook showing my new design;

FIG. 2 is another perspective view thereof;

FIG. 3 is a rear view thereof;

FIG. 4 is a left view thereof;

FIG. 5 is a right side view thereof;

FIG. 6 is a top side view thereof;

FIG. 7 is a bottom view thereof;

FIG. 8 is another bottom perspective view thereof; and,

FIG. 9 is another top perspective view thereof.

The broken lines show portions of the boat anchor hook and form no part of the claimed design.
